UNITED STATES PATENT OFFICE.

HERVY L. TRIMYER, OF PORTSMOUTH, VIRGINIA.

TRANSOM-LIFTER.

SPECIFICATION forming part of Letters Patent No. 773,352, dated October 25, 1904.

Application filed May 31, 1904. Serial No. 210,505. (No model.)

To all whom it may concern:

Be it known that I, HERVY L. TRIMYER, a citizen of the United States, residing at Portsmouth, in the county of Norfolk and State of Virginia, have invented certain new and useful Improvements in Transom-Lifters; and I do hereby declare the following to be a full, clear, and exact description of the invention, such as will enable others skilled in the art to which it appertains to make and use the same.

My invention relates to combined transom-lifters and pivots for hanging sash in the decks of railroad-cars and other places.

The invention is designed as an improvement upon the device shown and described in United States Letters Patent No. 746,495, issued to John H. Glassburn December 8, 1903; and its object is to provide a separate device which can be readily applied to the transom-lifter to prevent undue lateral movement of the sash which frequently results in displacement of the operating parts of the fixture and dislodgment of the sash, causing it to fall into the car and to sometimes injure its occupants.

In the drawings which form a part hereof, Figure 1 is a perspective view of the combined transom-lifter and pivot in operative position in conjunction with the sash and its casing and having my improvement applied thereto. Fig. 2 is a vertical section of the fixture and my improvement detached from the sash and casing, and Fig. 3 is a perspective view of my improvement detached from the ratchet.

In the said drawings corresponding parts in the several figures thereof are indicated by similar letters and numerals marked thereon.

A represents the frame, and B the sash.

40 C represents the lifter or ratchet part of the fixture, secured to the frame, and D the pivot part, secured to the sash in the usual manner. The lifter or ratchet C consists of an extended plate 1, provided with a seat or bearing 2 and having a casing or housing 3, through the ends of which operates a bolt 4, actuated by a coiled spring 5, one end of said spring bearing against the inner side of the upper end wall of the casing and the opposite end bearing

against a collar 6 on the bolt 4. The pivot 50 D consists of a plate 7, provided with a standard 8, at the outer end of which there is a stop 9 and from which a curved section 10 extends to and unites with the said plate at 11, the said curved section being provided 55 with a number of corrugations, the contour of which is such as to form a rest in each of the same and to hold the sash in either of the several positions represented thereby through the medium of the said bolt 4 operating under pressure of the spring 5. The said standard is provided with laterally-extending trunnions 12, one of which operates in the bearing 2 of the ratchet C.

The fixture represented in the foregoing 65 description is the same in construction and operation as that shown and described in United States Letters Patent No. 237,973, issued to Hart and Bissell February 22, 1881, and in itself constitutes no part of my invention. It has developed, however, that such fixtures are faulty in that they are not provided with means for preventing the sash from falling from its mountings when there is sufficient lateral movement to permit of 70 same, which is frequently the case and which has resulted in numerous accidents to passengers in railroad-cars.

As the said device has been used extensively for mounting deck-sash in passenger-cars, much thought has been given to devising means for overcoming the aforesaid objection, which can be applied to the fixtures already in use, thereby saving the expense of new fixtures and at the same time accomplishing the desired result at a trifling cost. Therefore to that end my present invention consists in a separate member E, formed with angle portions 13 and 14 and a return portion 15, the angle portion 13 having a screw-hole 16, 80 which registers with a corresponding screw-hole in the said extended plate 1 of the lifter or ratchet C, and thus by removing the screw by which at this point the fixture is secured to the woodwork the said member E can be applied. The angle portion 14 being provided with a perforation 17, through which the operating end of the bolt 4 moves, and with the

return portion 15, extending down over the rim of the curved section 10, as shown, the sash is guarded against undue displacement.

The advantages of my said improvement 5 will at once be apparent to those interested in the use of the fixture to which it is adapted, especially as it constitutes a separate article of manufacture which can be sold as such and applied to said fixtures irrespective of 10 where they may have been purchased or obtained.

Having thus fully described my invention, I claim as new and desire to secure by Letters Patent—

15 1. The combination with a transom-lifter and pivot, of a separate member perforated to receive one of the screws by which the lifter is secured to the woodwork and adapted to be held in position on said lifter by said 20 screw, the said member having a return portion extending down over the pivot-section to prevent undue lateral movement of the sash.

2. The combination with a transom-lifter and pivot, of a separate member having a

perforation through which the operating-bolt 25 of the lifter moves and a return portion extending down over the rim of the pivot-section to prevent undue displacement of the sash.

3. The combination with a transom-lifter and pivot, of a separate member comprising 30 the angle portions 13 and 14 and return portion 15 and adapted to be secured to the fixture in the manner described.

4. As a new article of manufacture adapted to be applied to transom-lifters to prevent 35 undue displacement of sash, a separate member comprising the angle portions 13 and 14 and return portion 15, the portion 13 being provided with a screw-hole and the portion 14 with a perforation, as and for the purposes set 40 forth.

In testimony whereof I hereunto affix my signature, in presence of two witnesses, this 26th day of May, 1904.

H. L. TRIMYER.
